United States Patent Office

Des. 199,182
Patented Sept. 22, 1964

199,182

HOSE SUPPORTER

Elton W. Burch, Savage, Minn., assignor to Progress Holding Corporation, Savage, Minn., a corporation of Minnesota

Filed May 3, 1963, Ser. No. 74,742

Term of patent 14 years

(Cl. D17—8)

FIG. 1 is a perspective view of a hose supporter showing my new design;

FIG. 2 is a front elevational view on a reduced scale;

FIG. 3 is a top plan view thereof;

FIG. 4 is a bottom plan view thereof;

FIG. 5 is a side elevational view looking from the right of FIG. 2; and

FIG. 6 is a rear elevational view of the design shown in FIG. 2.

I claim:

The ornamental design for a hose supporter, as shown.
